UNITED STATES PATENT OFFICE.

CHARLES W. J. SPECHT, OF FAIRVIEW, OKLAHOMA.

MEDICAL APPLIANCE.

1,115,981.

Specification of Letters Patent.

Patented Nov. 3, 1914.

Application filed January 6, 1914. Serial No. 810,621.

To all whom it may concern:

Be it known that I, CHARLES W. J. SPECHT, a citizen of the United States, residing at Fairview, in the county of Major and State of Oklahoma, have invented certain new and useful Improvements in Medical Appliances, of which the following is a specification.

My invention relates to a new and improved medical appliance, the object of my invention being the provision of an appliance or device adapted to stimulate the nerve centers of a patient and in this manner restore health.

My invention comprehends the provision of an apparatus for simultaneously rubbing or massaging the patient and for applying the water, liniment or other bath to the parts being treated.

A further object of my invention is the provision of a receptacle for holding the bath provided with a massaging device mounted upon the receptacle and extending partially within the same, the receptacle and massaging device being so arranged that a portion of the receptacle may be utilized as a support for the patient being treated. In this connection I provide a rotatably mounted drum, the outer peripheral face of which is covered with cloth or other absorbent material, the said material being adapted to take up a part of the liquid contained in the receptacle and rub it into that portion of the patient's body to be treated.

Other minor objects which I have in view are the provision of a simple means for securing the fabric to the drum, the provision of a drum, the periphery of which is concavo-convex to permit a closer application of portions of the body to the apparatus, the provision of removable supporting legs for the receptacle and the provision of a bracket or table forming a support for the patient.

With these and other objects in view, my invention will be more fully described, illustrated in the accompanying drawing, and then specifically pointed out in the claims which are attached to and form a part of this application.

In the drawing:—Figure 1 is a perspective view of my improved apparatus; Fig. 2 is a detail sectional view taken transversely of the drum through the line 2—2

of Fig. 3; Fig. 3 is a fragmentary sectional view taken through the line 3—3 of Fig. 2.

Corresponding and like parts are referred to in the following description and indicated in all the views of the drawing by the same reference characters.

In its simplest form, the preferred embodiment of my invention, as illustrated in the drawing, includes a liquid or bath holding receptacle 10 and a rubbing or massaging apparatus 11.

The receptacle 10, which is preferably semi-cylindrical in shape and open at its upper end, is formed with side members 12 and 13 of sheet metal, each substantially semi-circular in shape and each having its peripheral edge portion bent or deflected at right angles to the body portion to provide a flange 14. These side members are secured in proper spaced relation by a strip 15 of sheet metal which forms the bottom and ends of the receptacle, this strip being substantially rectangular in shape and engaging by its longitudinal edges against the inner faces of the sides 12 and 13.

The strip 15 is curved longitudinally to bear throughout its length against the inner faces of the flanges 14 of the sides and is secured in place by soldering or by any other preferred means. As clearly shown in Fig. 1, the ends of this strip project beyond the upper edges of the receptacle formed by the strip 15 and sides 12 and 13, one of the extensions being curved longitudinally to provide an apron 16 forming in effect a continuation of the end of the receptacle and the other end of the strip being bent outwardly to provide a table portion 17 lying in the plane of the upper edges of the receptacle.

The upper edge portions of the sides of the receptacle are reinforced by strips of sheet metal 18 which are preferably soldered to the outer faces of the sides 12 and 13 and additionally secured by any suitable means such as rivets 19. These strips, which are relatively wide, extend throughout the entire length of the receptacle and adjacent their end portions are bent outwardly to provide socket forming loops 20 to detachably receive the upper ends of supporting legs 21. These supporting legs, which are preferably formed of metal, are L-shaped in section including the body portions 22 equal in width to the width of the sockets 110

20 and the outwardly directed, relatively narrow flanges 23 which are cut-away at their upper ends to engage against the lower edges of the strips 18 and limit the movement of the legs into the sockets. These flanges 23 also serve to stiffen and otherwise strengthen the legs, enabling them to support considerably more weight than would be possible otherwise. The lower 10 ends of the flanges 23 are cut-away and the lower ends of the body portions 22 of the supporting legs are bent outwardly at right angles to form feet 24 in order to insure a steady and uniform support for the receptacle. The receptacle is preferably provided at its lowest point with a drain cock 15 25 of any suitable construction.

Secured to the outer faces of the strips 18 adjacent the upper edges of the receptacle and centrally of said strips, are alined, 20 two-part bearings 26 which receive the reduced end portions 27 of the hub 28 of the massage device or drum 11. This drum includes the hub 28, the rim or body portion 25 29 and a plurality of radially extending resilient spokes 30 connecting the hub and body portion of the drum. The body portion 29 of the drum is formed from a single strip of resilient metal bent into annular 30 form, as clearly shown in Fig. 1, and also curved transversely throughout its length as shown in Fig. 2 by which means a drum is provided, the outer face of which is convexed transversely. The end portions of the 35 body member 29 overlap each other to provide a lap joint and are detachably secured in place by a threaded stud 31, the head of which is countersunk in the outer or overlapping end portion of the body and the 40 shank of which extends through a perforation 32 formed in the inner or overlapped end of the body. Threaded upon this stud is a wing nut 33 by means of which the overlapping end portions of the body 29 may be 45 drawn together. The fabric covering 34 of this massage drum is formed from a single piece of fabric of any suitable weave and quality, a comparatively rough, coarse fabric being preferred, and this covering is secured upon the drum by inserting one end 50 thereof between the overlapping ends of the body member 29 and clamping it in place by tightening the wing nut 33. The strip of fabric is then wound about the periphery 55 of the drum in the manner clearly shown in Fig. 1 of the drawing, the fabric preferably being of such length as to pass two or three times completely about the drum, the outer end of the fabric being left free and unattached.

In order to provide means for rotating the drum, one end of the hub 28 is extended beyond the adjacent bearing 26 and provided with a crank arm 35 secured to the hub in any suitable manner as by a set nut

36 and provided at its free end with a handle 37. The drum, in use, is rotated in such a manner that that portion of its periphery passing the shelf or table 17 of the receptacle will be moving upwardly. In other words, the drum shown in Fig. 1 would be turned in a clockwise direction. It should be noted at this point, that the fabric strip 34 is wound about the periphery of the drum in the opposite direction from that in which the drum is to rotate, in this case in a counterclockwise direction.

In employing my improved medical appliance, a sufficient quantity of the liquid which is to be employed in the treatment is placed in the receptacle, enough being always employed to partially submerge the drum 11. The patient is then placed partially or wholly upon the shelf or table 17 in such a position that that portion of the patient's body to be treated will be in engagement with the peripheral face of the drum and the drum is then rotated in the direction indicated by the arrow. It will be clear that the fabric covering of the drum will become saturated with the liquid contained in the receptacle and it will therefore apply and thoroughly rub such liquid into the body of the patient. The convex outer face of the drum tends to prevent displacement of the fabric covering when the latter is once saturated with the liquid and also permits closer application of the body of the patient to the drum. The liquid employed is usually hot or cold water depending upon the complaint for which the patient is being treated, although oils or other liniments may be employed in the place of water. Because of the form of clamp illustrated for securing the fabric strip in place, it will be clear that after treating the patient, the fabric may be readily removed and a fresh strip substituted in its place.

Although I have illustrated and described my improved appliance in all its details, it will of course be understood that I do not wish in any way to limit myself to the specific details set forth, as various minor changes in construction, within the scope of the appended claims, may be made at any time without in the slightest degree departing from the spirit of my invention. For instance I do not wish to limit myself to the employment of a hand crank for rotating the massage drum as the same may be driven by power transmitted from an electric or water motor or other suitable source, if preferred.

Having thus described the invention, what is claimed as new is:

1. A medical appliance including a rotatable massage drum having an annular body portion with detachable overlapping ends, and means for clamping the ends together.

2. A medical appliance including a rotatable massage drum having an annular body portion with detachable overlapping ends, means for clamping the ends together, 5 and a strip of fabric clamped by one end between the overlapping ends of the body member and wound about the periphery of the drum.

3. A medical appliance including a semi-10 cylindrical receptacle provided at one end with an upstanding apron, and a soft surfaced massage drum mounted for rotation and extending partially within the receptacle.

15 4. A medical appliance including a bath holding receptacle provided at one end with a laterally directed shelf, a massage drum mounted for rotation and extending partially within the receptacle, the peripheral 20 face of the drum being disposed adjacent the shelf, and an absorbent covering for the drum.

5. A medical appliance including a receptacle, an upwardly directed apron at one end 25 of the receptacle, a laterally extending shelf at the opposite end of the receptacle, and a massage drum having a covering extending partially within the receptacle and mounted

for rotation about an axis extending transversely of the receptacle and intermediate its 30 length.

6. A medical appliance including a rotatable massage drum having an annular resilient body portion with detachable overlapping ends, a threaded stud carried by one 35 end and passable inwardly through a perforation formed in the other end, a clamping nut for such stud to clamp the overlapping ends together, and a strip of fabric having one end clamped between the overlapping 40 ends and its opposite end free of attachment.

7. A medical appliance including a bath holding receptacle, a rotatable massage drum carried by the receptacle, the peripheral face of the drum being convex transversely, and a covering of fabric secured by one end to the drum and wound about it peripherally, the other end of the fabric being free of attachment.

In testimony whereof I affix my signature 50 in presence of two witnesses.
